UNITED STATES PATENT OFFICE.

WILLIAM DAHL, OF FUNKSTOWN, MARYLAND.

RAILWAY-TIE.

1,054,281.

Specification of Letters Patent. Patented Feb. 25, 1913.

Application filed June 20, 1912. Serial No. 704,851.

To all whom it may concern:

Be it known that I, WILLIAM DAHL, citizen of the United States, residing at Funkstown, in the county of Washington and 5 State of Maryland, have invented certain new and useful Improvements in Railway-Ties, of which the following is a specification.

My invention relates to new and useful 10 improvements in railway ties and more particularly to metallic ties, and the object of my invention is to provide an improved form of metallic tie of the type in which wooden rail supporting blocks are mounted 15 and held against movement in a metal frame which is embedded in the ballast of the road in the same manner as the usual wooden tie.

A further object of my invention is to 20 provide a metal tie in which the central portion of the tie is open vertically to permit the positioning of the crushed rock or other ballast of a road bed and to more firmly bank the tie in place, this construction 25 also giving a slight resiliency to the central portion of the tie rendering the same more serviceable and of greater value in road beds where the ground is frozen during a portion of the year.

30 A further object of my invention is to provide a metallic frame for holding the rail supporting blocks and a plurality of braces for the frame which not only stiffen the frame but also serve to lock the blocks 35 against movement when the rails are in position thereon.

A further object of my invention is to provide certain of the above mentioned 40 braces with extended portions or flanges which engage against the outer portions of the rails to prevent the rails from spreading, this not only simplifying the laying of the track but also reducing the number of spikes employed in securing the rails in 45 position and thereby avoiding the danger of splitting the rail supporting blocks, the splitting of the blocks being a common occurrence in ties in which the sole securing means for the rails consists of spikes driven 50 into the blocks.

A further object of my invention is to so construct the rail engaging flanges of the braces as to adapt them for use in connection with fish plates in the formation of an 55 extremely rigid and strong rail joint for securing the adjacent ends of rails together.

With these and other objects in view, the invention will be more fully described, illustrated in the accompanying drawing, and then specifically pointed out in the claims 60 which are attached to and form a part of this application.

In the drawing: Figure 1 is a perspective view of my improved tie, showing the rails in place thereon and showing the employment of the rail engaging flanges in connection with a fish plate for forming a rail joint; Fig. 2 is a central longitudinal sectional view of the tie, the blocks being removed to more clearly show the construction of the tie proper; Fig. 3 is a vertical transverse section on the line 3—3 of Fig. 2, more clearly bringing out the arrangement of certain of the braces, particularly the rail engaging braces. 75

Corresponding and like parts are referred to in the following description and indicated in all the views of the drawing by the same reference characters.

As previously stated my improved tie is 80 of that type in which a metallic frame supports blocks of wood which form bearings for the rails and said tie includes block holding end members, side members or plates secured to the side portions of the 85 ends members and maintain the same in proper spaced and alined position, base plates forming tie supporting members and extending beyond the ends of the tie proper, braces stiffening the frame and also locking 90 the blocks in place, and additional braces for the frame arranged to engage the outer portions of the rails to lock the same against spreading movement on the tie.

Referring more specifically to the drawing, each tie includes a pair of spaced end members 10, each formed in a single piece and U-shaped in section, having a horizontal base web 11 and spaced side webs 12. Each of these members has its side webs 100 cut-away or otherwise shaped to form upwardly-extended shoulders 13 at their ends, the function of which will be hereinafter explained. These end members form a seat for the wooden rail supporting blocks 14 105 and are secured together in proper spaced apart, alined position by side members or plates 15, the end portions of which are riveted to the side webs of the members 10, the heads of the rivets being preferably 110 countersunk in the inner faces of the side webs 12 as shown at 16 in Fig. 3 to permit

the close engagement of the rail supporting blocks by the block holding members.

Secured to the lower face of the horizontal web portions 11 of the end members are 5 base plates 17, the outer ends of which extend beyond the outer ends of the block holding members and the inner ends of which extend beyond the inner ends and terminate in spaced relation as shown in Fig. 2. These base plates are preferably 10 of such a width as to not only extend beneath the block holding members but to also extend by their side edges beneath the lower edges of the side plates 15 and said base 15 plates are secured to the horizontal webs of the end members by rivets in the same manner as are the side plates.

The members thus far described constitute the main body or frame of the tie, the other 20 parts shown in the drawing and hereinafter described consisting chiefly of braces for strengthening the tie and securing the rail supporting blocks in place. The outer extended ends of each of the base plates 17 25 are strengthened and reinforced by leveling plates 18 equal in thickness to the thickness of the horizontal web portions of the end members and therefore leveling the outer ends of the base plates therewith to form a 30 support for the blocks should the latter extend slightly beyond the ends of the block holding members. In like manner, the end portions of the base plates which extend inwardly beyond the block holding members 35 are strengthened and leveled by similar plates 19, all of these leveling plates being secured to the base plates by rivets or other preferred means. These leveling plates 19 permit the insertion of one of the blocks 14 40 in the central portion of the rail when necessary for the positioning of a frog or switch rail and the central portion of the frame between the adjacent ends of the block supporting members is preferably equal in 45 length to the length of one of the block supporting members.

The side plates 15 of the frame are braced against inward movement toward each other by U-shaped braces 20 which are secured by 50 their side portions to the inner faces of the side members and which bear by their base portions against the inner edges of the block receiving members and consequently against the inner ends of the blocks when the latter 55 are in position. These braces are preferably formed from metal of the same thickness as the block holding members and consequently a block formed to fit snugly in one of the block holding members will fit 60 snugly between these braces and will be supported by the extended inner ends of the base plates and by the leveling plates carried thereby.

In order to prevent spreading of the side 65 plates of the tie and also to hold the blocks

against upward movement, I have provided U-shaped braces 21, the body portions of which extend across the inner ends of the blocks when the latter are in place and the side portions of which are riveted or otherwise secured to the outer faces of the tie by a portion of the same rivets 16 which secure the side plates to the block holding members. Additional U-shaped braces 22 are secured across the outer ends of each of the block holding members, the side portions of these braces bearing against the outer faces of the shoulders 13 to which they are riveted, while the body portion extends transversely of the tie between said shoulders. These braces 22 are provided at their inner sides with upwardly directed extensions or flanges 23 which bear over the outer flanges of the rails when the latter are in place, the edges of the rail flanges seating 80 against the inner ends of the shoulders 13 and being thereby held against outward movement upon the tie.

Combined braces and rail engaging members 24 are mounted upon the body portions 90 of the braces 22 and comprise U-shaped members, the side portions 25 of which are riveted to the end portions of the side plates 15 and the body portions of which rest upon the body portions of the braces 22 and have 95 extensions 26 bearing upon the extensions 23 of the braces 22 and terminating in vertically directed flanges 27 which engage against the outer faces of fish plates carried by the rails and which are perforated as 100 shown at 28' to receive bolts which pass through said flanges, the fish plates and rail to secure the rail in place.

In operation, the blocks are positioned in the block holding members as shown in Fig. 105 1 and the tie is properly positioned and ballasted in the usual manner, ballast also being positioned between the inner ends of the blocks and the side portions of the side members to additionally anchor the tie in 110 place. The rails are then positioned upon the tie and moved to bring their outer flanges beneath the extensions 23 and 26 of the braces 22 and 24 and against the inner 115 ends of the shoulders 13.

In Fig. 1 I have shown conventional rails 28' applied to the tie and fish plates 29 positioned upon either side of the rail webs, the outer fish plate being positioned between the vertical web of the rail and the flange 27. 120 Bolts 30 are passed through the perforations of these flanges, through the fish plates and through the vertical rail webs and are secured in place by nuts 31.

It will of course be understood that the 125 fish plates may be done away with if desired and the braces which engage the rail proportioned and arranged to engage directly against the vertical web of the rail. When so employed, the flanged portion 27 130

of the brace 24 will take the place of a fish plate at a rail joint and but one fish plate will be necessary, said plate being of course applied against the inner face of the rail

5 web to co-act with the flange 27.

From the foregoing description, taken in connection with the drawing, it will be apparent that I have provided an extremely simple and efficient form of metallic tie and 10 one in which the main frame of the tie is firmly braced by braces which also serve to hold the rail supporting blocks in position and to hold the rails against spreading movement upon the tie.

15 It will of course be understood that various changes in the details of construction, such as the omission of the leveling plates, or the extending of the horizontal web portions of the block holding members to take the 20 place of the base plates, may be made if desired, without in the slightest degree departing from the spirit of my invention.

The outwardly extended ends of the base plates is one of the important features of the 25 invention in that it gives an added supporting area to the tie, thereby permitting the leaving of the central portion of the tie open for ballast and also because the ballast may be banked against the ends of the tie 30 and over said extended portions to further anchor the same in place.

The inner flanges of the rail are secured in place by the customary spikes 32 driven into the blocks 14 and it will be apparent 35 that the blocks may be readily removed and renewed when decayed or otherwise unfit for use by the simple withdrawal of these spikes, the blocks being driven out of the ends of the tie by blows administered against 40 their inner ends, the braces 20 being so proportioned as to expose the inner ends of the blocks for this purpose.

Having thus described the invention, what is claimed as new is:

45 1. A metallic tie including block receiving members, side members connecting said block receiving members, and base plates secured to said block receiving members and having their inner ends spaced apart and their outer 50 ends extended beyond the outer ends of the block receiving members, said base members being equal in width to the block receiving members.

2. A metallic tie including block receiving 55 end members, side members connecting the end members, base plates secured to the end members and extending at their ends beyond the same, braces extending between the side members and acting as stops to limit 60 the inward movement of the blocks, and

braces extended transversely over the blocks to limit their upward movement and having their ends secured to the outer faces of the side members.

3. A metallic tie including a frame having 65 block receiving end portions including side members and base plates, brace members extending transversely of the tie and having their side portions secured to the side members, and extensions formed integrally with 70 said braces and adapted to engage over the outer flanges of a rail.

4. A metallic tie including block receiving ends members, side members connecting the end members, base plates, and braces for the 75 side members including flanged extensions engaging over the outer rail flanges and bearing against the web of the rail.

5. A metallic tie including end members having a horizontal web and upwardly directed spaced side webs, the outer ends of which are provided with upwardly extended shoulders adapted to receive the outer flange of a rail, and braces connecting said shoulders adapted to bear over the outer rail 85 flange.

6. A metallic tie including end members having a horizontal web and upwardly directed spaced side webs, the outer ends of which are provided with upwardly extended 90 shoulders adapted to receive the outer flange of a rail, braces connecting said shoulders adapted to bear over the outer rail flange, and additional braces bearing over the first 95 braces and having vertical flanges at their inner edges adapted to bear against the web of the rail.

7. A metallic tie including block holding end members having a horizontal web and upwardly directed spaced side webs, the 100 ends of said members being open, side plates equal in height to the side webs of the block holding members and secured thereto to maintain the block holding members in spaced relation, and base members equal in 105 width to the width of the horizontal webs of the block holding members and secured thereto, the outer ends of said base members extending beyond the outer ends of the block holding members and the inner ends of said 110 base members extending beyond the inner ends of the block holding members but terminating in spaced relation to each other.

In testimony whereof I affix my signature in presence of two witnesses.
